INVENTOR

F. E. Monteverde.

UNITED STATES PATENT OFFICE.

FLORENCIO E. MONTEVERDE, OF SAN FRANCISCO, CALIFORNIA.

PULP-DISTRIBUTER.

SPECIFICATION forming part of Letters Patent No. 431,607, dated July 8, 1890.

Application filed December 23, 1887. Serial No. 258,916. (No model.)

To all whom it may concern:

Be it known that I, FLORENCIO E. MONTEVERDE, a citizen of the United States, residing in the city and county of San Francisco, State 5 of California, have invented a certain new and useful Improvement in Pulp-Feeders for Concentrating-Machines, of which the following is a full, clear, and exact description.

My invention relates to an improved feeding apparatus for concentrating-machines, through which the pulp to be treated is conveyed directly upon the concentrating-pan near the outer periphery thereof, and more particularly to such machines or concentrators wherein a circular revolving pan is used 15 in connection therewith, as will hereinafter more fully appear in the drawings, and be pointed out and described in the specification.

My invention consists of a feeding apparatus attached to the end of the sluice or conduit designed to carry the pulp or material to be concentrated directly from the grinding or stamping mill to the concentrating-machine. This feeder consists of a central bowl 20 or hopper, preferably of conical shape, secured to the end of the sluice or conduit. Projecting from the lower part of said bowl or hopper are three, four, or more radiating 25 inclined troughs closed at their outer extremities, and said bowl or hopper is provided with suitable openings into each of these troughs, as clearly shown. These inclined troughs have a slight inclination or pitch downward 30 as they spring from the bowl to their outer extremities. The bottom of the bowl or hopper and of these inclined troughs, where they join, are on the same level; but the bottom of the inner side of the hopper I prefer to make 35 slightly conical or convex, so that the material or pulp dropping into the same may be evenly distributed to all the radiating troughs. To allow the pulp conveyed to the troughs in this manner to be discharged suitable openings are made in the bottom thereof nearest 40 their outer extremity.

This feeder is attached to the end of the sluice of the crushing or stamping mill, which projects forward as far as the center of the 45 pan of the concentrating-machine. The feeder is secured to the under side of said sluice by means of suitable ears or lugs attached to its

outer rim, by means of which it can be screwed on or nailed to the under side thereof, so as to be rigidly held in position.

55

Referring to the accompanying drawings, forming a part of this application, in which similar letters of reference are used to denote corresponding parts throughout the entire specification and several views of the 60 drawings, Figure 1 is a perspective view of my improved feeder as applied to the rotary concentrating-pan, and Fig. 2 is a vertical section of the same.

The letter A indicates the concentrating- 65 pan of the machine, while B is the sluice or trough leading from the stamping or crushing mill.

C is the central hopper or bowl of my improved feeder, from which radiate the inclined troughs or conduits D D. The outer extremity of these troughs have the perforations a a formed therein, through which the pulp running through the troughs is passed directly upon the concentrating-pan. The 70 central hopper or bowl C is provided with the ears or lugs b b, by means of which it is suitably connected to the under face of the sluice or conduit B, as clearly shown in the drawings.

80

From the foregoing it will be readily understood how my feeder is constructed and applied.

The advantages of such a constructed feeder 85 over others of a similar nature heretofore used for the purpose of feeding pulp to the concentrating-pan are obvious.

By the use of the feeder herein described, the pulp or material sought to be concentrated is brought at the nearest point possible to the level of the contents of the concentrating-pan and at the same time is discharged to the extreme inner periphery of the same, this being the point where all the heavy particles are saved or concentrated. The object 90 obtained by this means is twofold. First, as stated, the pulp is brought to the point where it is more favorable toward obtaining the best results from the rotary action of the concentrating-pan; second, by allowing the pulp 100 to pass out through the perforations or openings in the extremities of the radiating troughs immediately above the bed of the moving pulp contained within the pan of the concen-

trator it occasions the least possible disturbance in the peculiar currents produced by its movements in the process of working, thereby insuring a more perfect and thorough concentration, whereas by the methods heretofore used, which admitted the pulp to the pan at one part only of its periphery, which created currents and disturbances contrary to those produced by the machine in its actual working, great loss of the precious particles followed, by reason of the pulp being treated by oppositely-working currents, which necessarily forced or caused the same to a great extent to be carried off with the waste particles or gangue.

Having thus fully described my invention, what I claim as new, and desire to secure protection in by Letters Patent of the United States, is—

In an ore-concentrator, the combination, 20 with the circular revolving concentrating-pan A, of the sluice or conduit B, leading from the stamping-mill, central bowl or hopper C, provided with lugs or ears b b, for securing the same onto and beneath the end of the 25 sluice B, so as to receive the pulp fed from the mill, inclined troughs or conduits D D, radiating from the bowl or hopper C, provided at their extremities with apertures or 30 perforations a a, so as to enable the pulp fed through the conduit to be discharged near the periphery of the rotary concentrating-pan when in motion, substantially as shown and described.

FLORENCIO E. MONTEVERDE.
